Filed Apr. 13, 1959, Ser. No. 806,080

6 Claims. (Cl. 40—104)

This invention relates to improvements in a page turning device which may be employed for display or advertising purposes or for turning sheet music, book pages or the like.

The device comprising the present invention is characterized by its simplicity both of manufacture and of use, and is further characterized in that it is reliable in operation and can be manufactured most inexpensively.

There are two basic forms that the present invention may take, although many modifications may be made thereon. The two basic forms comprise, (1) the form wherein three or more pages are to be turned and (2) the form where two or less pages are to be moved.

In the first basic form of the invention, three or more pages are moved sequentially in one direction in one cycle and all of said pages are returned to initial position in the reverse cycle. In the second basic form two pages are moved sequentially in one direction in one cycle and are returned sequentially to initial position in the reverse cycle. Within the framework of these two basic forms many modifications are contemplated.

The objects, advantages and features of the present invention will be more apparent from the accompanying drawings and following detailed description.

In the drawings,

FIG. 1 is a top plan view of a device embodying the concepts of the present invention.

FIG. 2 is a front elevational view of the device shown in FIG. 1.

FIG. 3 is a side elevational view of the device on a reduced scale.

FIGS. 4, 5, 6, 7 and 8 are perspective views of the device on reduced scale showing sequential positions of the parts during operation.

FIGS. 9, 10, 11, 12, 13 and 14 are perspective views of an embodiment of the invention wherein two pages are turned sequentially in both directions, said views showing sequential positions of the parts.

Referring in detail to the drawings and with specific reference to FIGS. 1 to 8 inclusive the first basic form of the invention, hereinbefore referred to, is illustrated. In this form of the invention three pages are to be moved, but, if desired, the structure may be so contrived as to move three or more pages and such variation is contemplated herein.

The reference numeral 1 indicates generally a device embodying the concepts of the present invention. The device 1 comprises essentially a support or back 2 upon the front face of which three pages 3 are hingedly mounted; an actuating mechanism 4 for turning the pages, and a drive mechanism 5 for driving the actuating mechanism 4.

The support or back 2 comprises a relatively rigid sheet material, such as, stiff cardboard, a plastic or metal panel or the like, is generally rectangular in contour and is characterized in that the upper edge thereof is provided

2

with two spaced relatively large notches 6 and 7. Provided within each notch 6 and 7 is a smaller secondary notch 8 and 9, respectively. The spacial relationship of the notches relative to the opposite edges of the back is not of critical importance except to furnish adequate support for the pages on the back, but the spacial relationship of the notches is of critical importance with respect to the position of the actuating mechanism 4 and the hinge line of the pages 3, as will be hereinafter more fully described.

For convenience in mounting, the back may carry spaced easel supports 10 which may be locked in operative position by locking tabs 11, the easel supports and locking tabs being of conventional and well known construction.

The pages 3, designated 3a, 3b and 3c are in superimposed position and are hinged together along hinge line 12, the lateral edge portions 13 of the pages being secured together and also being secured to the back 2.

20 The pages 3 are characterized in that they are provided with corner notches at their upper right-hand corners, as viewed in FIG. 1. The page 3a is provided with corner notch 14a; page 3b is provided with corner notch 14b, and page 3c is provided with corner notch 14c, the notches being of different horizontal depths, as viewed in FIG. 1, notch 14a being of smallest depth, notch 14b being of medium depth and notch 14c being of greatest depth. Thus, when said pages are in the superimposed position shown in FIG. 1, hereinafter referred to as their initial position, the respective notches 14a, 14b and 14c will be in stepped position toward hinge line 12.

It will be noted that the hinge line 12 is offset from a line centrally spacing the notches 6 and 7 in back 2, that is, the hinge line is closer to notch 7 than it is to notch 6.

35 The reason for this arrangement will be apparent as the description proceeds.

The actuating mechanism 4 comprises essentially a shaft 15 carrying arms 16, 17 and 18. A metal strap 19 is secured to the rear face of the back adjacent its upper edge portion, the strap having a securing portion 20 disposed in plane-parallel relationship to the back; a lower normally extending bearing arm 21; an upper normally extending bearing arm 22 which terminates in a downwardly extending spacing arm 23 which, in turn, 40 carries an upwardly extending intermediate bearing arm 24. Shaft 15 extends through openings in the bearing arms 21, 22 and 24 and is rotatably positioned in said arms.

50 A hub 25 is carried at the upper end of shaft 15 and supports the radially extending arms 16, 17 and 18. Arm 16 is longer than arm 17 which, in turn, is longer than arm 18. Arm 16 carries a downwardly extending finger 26; arm 17 carries a downwardly extending finger 27, and arm 18 carries a downwardly extending finger 28, fingers 26 and 27 being of substantially equal length and finger 28 being longer than either finger 26 or 27.

55 It will be noted that the axis of shaft 15 is substantially midway disposed between notches 6 and 7, that is, said notches, including secondary notches 8 and 9 are substantially symmetrically disposed about shaft 15 as an axis.

During operation of the device 1, shaft 15 rotates in a cyclic manner and although the shaft may be rotated by any suitable type of prime mover, a unidirectional elec-

tric motor 29 has been found convenient. The motor 29 is secured by bolts 30 to the rear face of the back 2 below shaft 15. Formed in unitary fashion with the motor casing, a gear reducer-clutch mechanism casing 31 is carried, the output shaft 32 of which carries a gear 33 which meshes with gear 34 carried at the lower end of shaft 15. The gear reducer-clutch mechanism employed rotates shaft 15 in a predetermined direction through a predetermined angle and then reverses the direction of rotation of the shaft through the same angle. The gear reducer-clutch mechanism device is conventional and per se does not constitute part of the present invention. In operation, specific reference is made to FIGS. 4 to 8, inclusive, the pages 3 in this initial position, are in superimposed position to the left of the hinge line 12 as shown in FIG. 4, and the arm 16 is so positioned as to dispose finger 26 immediately behind back 2. Motor 29 is actuated and shaft 15 turns in a clockwise direction as viewed in FIG. 4. Finger 26 then passes through notch 7 in back 2 and through corner notches 14c and 14b of pages 3c and 3b and contacts page 3a between the vertical defining edges of notches 14a and 14b. As the shaft 15 continues its rotation, page 3a is swung about hinge line 12. Before page 3a reaches its 180° position, as shown in FIG. 5, finger 26 has moved relatively outwardly from the vertical edge defining corner notch 14a and said finger can thus move rearwardly of page 3a and the back 2 through notch 6. This movement is accomplished by virtue of the offset relationship of shaft 15 with respect to hinge line 12 in the plane of back 2.

At substantially the time when finger 26 passes through notch 6, finger 27 moves through notch 7 in back 2 and through corner notch 14 in page 3c and contacts page 3b. Page 3b is thus swung about hinge line 12. When page 3b approaches its 180° position, due to the length of arm 17 and the offset relationship of shaft 15 and hinge line 12, as hereinbefore described, finger 27 clears the lateral edge of page 3b and moves rearwardly of the back 2, the finger 27 passing through both corner notches 14 and 14b and notch 6.

When finger 27 moves substantially rearwardly of back 2, finger 28 of arm 18 contacts page 3c, as shown best in FIG. 6, and thereupon swings page 3c about hinge line 12. However, the length of arm 18 is so related to the position of shaft 15, the hinge line 12 and the position of the vertical defining edge of corner notch 14a of page 3a, that it does not swing around said vertical defining edge but would tend to abut page 3a.

However, finger 28 is longer than fingers 26 and 27 and when it moves through notch 7, it also moves through notch 7, it also moves through secondary notch 9. When page 3c has been moved to its 180° position, as shown in FIG. 7, finger 28 will tend to abut page 3c.

This constitutes one complete forward cycle of the mechanism 4, and before finger 28 completes its clockwise travel, as shown in FIG. 7, the mechanism 5 reverses the rotation of shaft 15 to commence the reverse cycle.

The device, as so far described, deals with the swinging of three pages in sequence. If more than three pages are swung, more progressively lengthened arms are employed similar to arms 16, 17 and 18. Moreover it will be found that the position of shaft 15 behind the plane of back 2 will be changed so that one page will substantially complete its swing before the next page commences its swinging.

When all pages have been swung clockwise, as shown in FIG. 7, and shaft 15 has reversed its rotation, finger 28 will move counterclockwise in front of back 2 and eventually said finger will pass through secondary notch 9. Finger 27 will then pass through notch 6 and all of the corner notches, as will finger 26, and eventually finger 28 will move to the position shown in FIG. 8. Finger 28 will then contact page 3a and will swing all of said pages simultaneously to their initial position. With the pages

in the initial position, shown in FIG. 4, finger 28 will lie in front of page 3a. This completes the reverse cycle and mechanism 31 will again reverse the direction of rotation of shaft 15. After a one-third revolution, the position shown in FIG. 4 will again be assumed by the parts. The cycle and reverse cycle will then repeat themselves.

Referring particularly to FIGS. 9 to 14 inclusive, 35 indicates generally a form of the invention wherein two pages may be turned sequentially in both the forward 10 cycle and the reverse cycle. The device 35 comprises essentially a back or support 36; a page turning mechanism 37 and pages 38, the latter comprising page 38a and page 38b.

The back or support 36 may comprise a panel of sheet 15 material similar to the back or panel 2, hereinbefore described and may carry at its rear a conventional easel support 39. The back or panel 36 is characterized in that two substantially similar notches 40 and 41 are provided adjacent the upper edge portion of the panel, said notches 20 being spaced from each other.

The pages 38a and 38b are hingedly secured to the front face of the panel and are hingedly secured to each other along hinge line 42. It will be noted that the notches are spaced unequally from the hinge line, the 25 notch 40 being further away from said hinge line than is notch 41.

The page turning mechanism 37 comprises a shaft 43 which is disposed substantially parallel to the hinge line 42, said shaft being rotatably mounted in a shaft support 30 44. The shaft support 44 is carried by the rear portion of panel 36 and is similar in general to the shaft support 19, hereinbefore described. It will be noted that shaft 43 is spaced rearwardly from the rear face of the back or panel, but not spaced as far rearwardly as is shaft 15, 35 hereinbefore described.

A hub 45 is carried by the upper portion of shaft 43 and two radial arms 46 and 47 extend outwardly from the hub in diametrically opposite directions. Arm 46 is shorter than arm 47 and arm 46 carries a downwardly 40 extending finger 48 and arm 47 carries a similar finger 49 of length shorter than finger 48. It will be noted that shaft 43 is disposed substantially centrally between notches 40 and 41, and hence, when shaft 43 is rotated the fingers 48 and 49 may pass through both notches 40 45 and 41.

The pages 38a and 38b are provided with notches 50 and 51, respectively. The notches 50 and 51 are so spaced relative to hinge line 42 that notch 50 registers with notch 40 and notch 51 registers with notch 41 when 50 the pages are disposed 180° apart, as shown best in FIGS. 10 and 13. Notches 50 and 51 are narrower in width than notches 40 and 41 and when the respective notches are in registration, as hereinbefore described, notch 50 is disposed adjacent an outer marginal edge of notch 40 and 55 notch 51 is disposed adjacent an opposite outer marginal edge of notch 41. Hence, when said notches are in respective registration, a solid portion 52 of page 38a overlies a portion of notch 40 and a solid portion 53 of page 38b overlies a portion of notch 41.

Shaft 43 may be rotated by any suitable means, but a device such as contemplated at 5, hereinbefore described, has been found convenient, that is, a device (not shown) which causes the shaft to rotate through a cycle; rotate 60 through a reverse cycle and continuously repeat such operation.

In the operation of the device illustrated and described in conjunction with FIGS. 9 to 14 inclusive, the position of the parts illustrated in FIG. 9 will be considered as the starting point of the operation. At this position of the 70 parts the shaft 43 will be rotating in a clockwise direction and both pages 38a and 38b will be positioned on the right side of the hinge line 42 as viewed in FIG. 9. As the shaft 43 rotates, the finger 49 passes through notch 41 in panel 36 and also passes through notch 51 of page 75 38b. Thus, the finger 49 contacts a solid portion of page

38a and swings page 38a about the hinge line 42 in a clockwise direction. As arm 47 and finger 49 approach the 180° position finger 49, because of the offset relationship of shaft 43 and hinge line 42, passes through notch 50 in page 38a and thereafter passes through notch 40 in panel 36. The parts will then be in the position illustrated in FIG. 10.

In the position shown in FIG. 10, after finger 49 has passed through notches 50 and 40, finger 48 passes through notch 41 in panel 36 and contacts a solid portion of page 38b. Finger 48 thereby swings page 38b about the hinge line 42 and both finger 48 and page 38b assume the position shown in FIG. 11. The forward cycle of movement of shaft 43 has been completed and the mechanism associated with said shaft reverses the rotary movement of said shaft to commence the reverse cycle.

At the initial stage of the reverse cycle finger 48 swings forwardly in front of the panel 36 in a counterclockwise direction as illustrated in FIG. 11. Eventually finger 48 moves through notch 41 in the panel and finger 49 passes through notch 50 of the panel, notch 50 of page 38a and contacts a solid portion of page 38b. This is the position of the parts shown in FIG. 12.

As the shaft 43 continues its reverse rotation finger 49 swings page 38b in a counterclockwise direction, as shown best in FIGS. 12 and 13 whereby page 38b moves to the position shown in FIG. 13. Because of the offset relationship of shaft 43 and hinge line 42, as finger 49 moves from the front portion of the panel to the rear portion thereof said finger moves through notch 51 in page 38b and notch 41 in panel 36. This is the position shown in FIG. 13.

As the shaft 43 continues its reverse rotation, finger 48 passes through notch 40 in panel 46 and contacts a solid portion of page 38a and swings said page through an arc of approximately 180° until the parts occupy the position shown best in FIG. 14. This completes the reverse cycle.

The shaft 43 then repeats its clockwise motion and commences the forward cycle. In the initial portion of the forward cycle the finger 48 moves forwardly in an arc in front of the panel 36 until the parts assume the position shown in FIG. 9. Thereafter the forward and reverse cycles are continuously repeated.

When page 38b is swung in the forward cycle, it will be noted that finger 48 moves past notch 51 in said page. In order to prevent said finger from passing through said notch, finger 48 is made longer than the vertical dimension of notch 51, and hence, continues to bear upon a solid portion of page 38b and continues to swing said page. Substantially the same arrangement is contemplated in the form of the invention shown in FIGS. 1 to 8, inclusive. The shorter fingers 26 and 27, when they bear upon pages 3a and 3b, respectively, bear upon solid portions of said pages for a sufficient degree of arc to move said pages to the 180° positions. Because of the horizontal length of corner notch 14c finger 28 is made longer than fingers 26 and 27 and finger 28 bears upon solid portions of page 3c below the horizontal defining edge of corner notch 14c.

As has been hereinbefore described, shaft 15 and shaft 43 are offset rearwardly from the planes of their respective panels. In general as the number of pages to be turned, and hence, the number of arms, increase, the distance of disposition of the actuating shaft behind the panel increases so that the fingers of adjacent arms will assume a position approximately in the plane of the panel during rotation of the actuating shaft.

We claim as our invention:

1. A page turning device comprising a support panel having opposite faces, a plurality of pages hingedly connected to the front face of said panel and to each other along a hinge line, a rotatable shaft carried by the rear face of said panel and disposed substantially parallel to

- and offset from said hinge line in the direction of the plane of the front face of the panel, angularly spaced radially extending arms of unequal length carried by said shaft, a finger transversely carried by each arm, said panel being provided with a pair of notches each being disposed a substantially equal distance on each side of said shaft, said notches being respectively disposed unequal distances on each side of said hinge line whereby all of said fingers may pass through all of said notches 5 when the shaft is rotated, said pages being provided with notches each being disposed unequal distances from both the shaft and the hinge line whereby when the shaft is rotated certain of said fingers pass through certain of said page notches and abut certain of said pages.
15. 2. A page turning device comprising a support panel having opposite faces, a plurality of pages hingedly connected to the front face of said panel and to each other along a hinge line, a rotatable shaft carried by the rear face of said panel and disposed substantially parallel to 20 and offset from said hinge line in the direction of the plane of the front face of the panel, angularly spaced radially extending arms of unequal length carried by said shaft, a finger transversely carried by each arm, said panel being provided with a pair of notches each being disposed a substantially equal distance on each side of said shaft, said notches being respectively disposed unequal distances on each side of said hinge line whereby all of said fingers may pass through all of said notches when the shaft is rotated, said pages being provided with 25 notches each being disposed progressively unequal distances from both the shaft and the hinge line whereby when the shaft is rotated certain of said fingers pass through certain of said page notches and abut certain of said pages.
30. 3. A page turning device comprising a support panel having opposite faces, a plurality of pages more than two hingedly connected to the front face of said panel and to each other along a hinge line, a rotatable shaft carried by the rear face of said panel and disposed substantially parallel to and offset from said hinge line in the direction of the plane of the front face of the panel, angularly spaced radially extending arms of unequal length corresponding in number to the number of pages carried by said shaft, a finger transversely carried by each arm, 40 said panel being provided with a pair of notches each being disposed a substantially equal distance on each side of said shaft, said notches being respectively disposed unequal distances on each side of said hinge line whereby all of said fingers may pass through all of said notches when the shaft is rotated, each of said pages being provided with a notch and each notch being disposed a progressively unequal distance from both the shaft and the hinge line when said pages are in stacked relationship on one side of said shaft whereby when the shaft is rotated 45 50 55 in a predetermined direction said fingers progressively abut said pages to turn said pages sequentially through an angle of about 180° to a reverse stacked position on the other side of said shaft.
4. A device as contemplated in claim 3 wherein reverse rotation of said shaft causes the finger carried by said shortest arm to abut the lowermost page of said reverse stack to swing all of said pages simultaneously to the initial stacked position.
5. A page turning device comprising a support panel 60 having opposite faces, a pair of pages hingedly connected to the front face of said panel and to each other along a hinge line, a rotatable shaft carried by the rear face of said panel and disposed substantially parallel to and offset from said hinge line in the direction of the plane of the front face of the panel, a pair of angularly spaced radially extending arms of unequal length carried by said shaft, a finger transversely carried by each arm, said panel being provided with a pair of notches each being disposed a substantially equal distance on each side of said shaft, said notches being respectively disposed un-

equal distances on each side of said hinge line whereby all of said fingers may pass through all of said notches when the shaft is rotated, said pages being provided with notches each being disposed unequal distances from both the shaft and the hinge line when said pages are in stacked relationship on one side of said shaft whereby when the shaft is rotated one of said fingers passes through one of said page notches and the other finger abuts the remaining page sequentially to swing said pages through an angle of about 180° to a reversed stacked position on the other side of said shaft. 10

6. A device as contemplated in claim 5 wherein reverse rotation of said shaft causes the fingers to sequentially abut the pages and swing them through about 180° to initial stacked position.
